GLASS BLOCK

Veli Tappio Virkkala, Helsinki, Finland, assignor to A. Ahlstrom Osakeyhtio, Noormarkku, Finland, a joint-stock company of Finland

Filed May 6, 1963, Ser. No. 74,760

Term of patent 14 years

(Cl. D18—2)

FIG. 1 is a top plan view of a glass block showing the design according to the present invention; and

FIG. 2 is a side elevation view of the block of FIG. 1.

The bottom surface is the same as the top surface shown in FIG. 1, and the other sides are the same as the side shown in FIG. 2.

I claim:

The ornamental design for a glass block, as shown and described.
